UNITED STATES PATENT OFFICE.

WILLIAM F. GRUPE, OF HUDSON HEIGHTS, NEW JERSEY, ASSIGNOR TO ENDLESS BELT CORPORATION, INC., A CORPORATION OF NEW YORK.

HOPPER FOR CIGARETTE-MAKING MACHINES.

Application filed October 10, 1919. Serial No. 329,829.

This invention relates to cigarette making machines.

An object of this invention is to provide means for attaining uniformity of the produced cigarettes.

In cigarette making machines in present use and as heretofore proposed the produced cigarettes vary individually in total tobacco content as well as in the distribution and 10 density of the tobacco within the paper wrapper or container. Such defects in the produced cigarettes I have discovered, arise from the inherent defects of the arrangement and construction of the means for agitating and feeding of the tobacco in the 15 hopper.

As a result of such inherent defects, the produced cigarettes are not uniform in smoking qualities, owing to the absence of 20 uniform distribution and density of the contained tobacco. As another result, it has been necessary to over-charge the tobacco fed into the hopper to satisfy the requirements of the internal revenue and other 25 laws, so that in fact a surplus quantity of tobacco has been necessary in the manufacture of cigarettes by such prior machines.

I have discovered that the aforesaid defects are overcome by providing a hopper 30 for cigarette making machines comprising, in the more preferred forms of my invention, a plurality of sets of carding mechanisms arranged to jointly subject the charge of tobacco within the hopper to agitating 35 forces varying in degree, direction and effective period, whereby lumps or felted masses of tobacco are "broken up" and the charge as a whole is fed uniformly to the carding mechanism and uniformly delivered 40 by the same to the delivery apron to the cigarette rod forming mechanism of the machine. In such more preferred forms of my invention, the delivery to the apron is in the form of a plurality of streams of tobacco 45 supplied by the respective carding mechanisms.

Further features and objects of the invention will be more fully understood from the following description and the accompanying drawings, in which—

Fig. 1 is a vertical central sectional elevation showing one embodiment of my hopper;

Fig. 2 is a vertical central sectional elevation showing a modification;

Fig. 3 is a diagrammatic vertical eleva-

tion of the driving mechanisms of parts of the aforesaid constructions;

Fig. 4 is a detail side elevation showing the common driving mechanism, with individually varied regulating means for the respective sets of carding mechanisms; and 60

Fig. 5 is a plan view of parts of Fig. 4.

Referring to Fig. 1, the hopper 1 comprises the oppositely disposed end frames 2, only one being shown and the oppositely 65 disposed side frames 3, 3, provided with the usual hinged doors, 4, 4.

Within the hopper 1 is arranged one set of carding mechanism comprising the upper roll 5 and also lower carding roll 6, the 70 aforesaid being driven in opposite directions and preferably the former in the direction of the arrow 9 and the latter in the direction of the arrow 10. The roll 5 is mounted on its shaft 7 and the roll 6 on its shaft 8, 75 these shafts being driven by suitable driving mechanism, as appears more fully hereinafter. The roll 5 serves to level the tobacco taken up by the pins of the carding roll 6. Coacting with the aforesaid rolls 80 5, 6, are arranged the pin roll 11 mounted on its shaft 12, and driven by suitable gearing in the direction of the arrow 13, and the paddle wheel 14 mounted on a suitable shaft and driven in the direction of the 85 arrow 15.

The other carding mechanism comprises the upper or leveling roll 16 and the lower or carding roll 17, the former being mounted on its shaft 18 and the latter on its 90 shaft 19 and respectively driven in counter directions indicated by the respective arrows 20, 21. Coacting therewith is arranged the pin roll 22 driven in the direction of the arrow 24 and the paddle wheel 25 driven in 95 the direction of the arrow 26. The aforesaid sets of carding mechanisms may comprise the usual wipers 104, 104.

In Fig. 3 I have shown one form of suitable mechanism for imparting the desired 100 motions to the aforesaid respective parts of the sets of carding rolls. The main shaft of the cigarette machine is indicated at 40 provided with the belt pulley 41. Fixed to the main shaft 40, see also Fig. 4, are the 105 cone pulleys 42, 43, coacting respectively with the oppositely arranged cone pulleys 44, 45, and the crossed belts 46, 47. The cone pulley 44 is fixed on the shaft 48 controlling generally the drive of the sets of card- 110

ing rolls and associated devices shown to the right in Fig. 1 and the cone pulley 45 is fixed on the shaft 49 controlling generally the drive of the set of carding rolls and associated devices shown to the left in Fig. 1.

Specifically, the countershaft 50 is driven from the shaft 48 by suitable gearing, driving in turn by means of the chain 51 the sprocket gear 52, and thereby the shaft 10 7 of the carding roll 5 by means of the pawl 53 and ratchet gear 54, in the usual approved manner. Such sprocket 53 drives the shaft 8 of the carding roll 6 by the suitable gearing as indicated. The shaft 15 12 of the pin wheel 13 and the shaft 55 of the paddle wheel 14 are driven by the chain 56, driven by the sprocket 57 meshing with the sprocket on the shaft 50, as indicated.

In a similar manner, the shaft 18 of the 20 carding roll 16 is controlled by the counter shaft 49 through the chain 58 and associated sprocket wheels and gearing, thereby in turn driving the shaft 19 of the carding roll 17. Similarly, the shaft 23 of the pin 25 wheel 22 and the shaft 59 of the paddle wheel 25 are controlled by the counter shaft 49 through the chain 60 and associated sprocket wheels and gearing as indicated.

Thus, upon drive of the main shaft 40 30 in clockwise direction, as viewed in Fig. 3, the carding wheel 5 is rotated in the direction of the arrow 9, its associated carding wheel 6 rotated in the direction of the arrow 10, of the one set, and the carding wheel 35 16 rotated in the direction of the arrow 20 and the carding wheel 17 in the direction of the arrow 21, of the other set, the other associated parts being rotated in proper relative direction of rotation as hereinabove 40 set forth.

As a result of the aforesaid arrangement 45 the charge of tobacco positioned between the rolls of the respective sets is subjected to the intermittent forces directed in transverse directions arising from the intermittent drive of the uppermost rolls 5, 16. As any given portion of the charge of 50 tobacco descends within the hopper, it is subjected to further forces directed in transverse directions and continuous in period. By such arrangement of varying 55 forces, the tobacco is agitated in such manner whereby the formation of air pockets is precluded and lumps or felted masses which may be present in the initial charge, is precluded.

Further, the directions of the forces of agitation are from the respective sets generally toward the opposite sets, whereby the 60 charge of tobacco is fed substantially uniformly in contact with the respective rolls and thus uniformly carded by the respective carding rolls individually. The carded tobacco is delivered in the form of a plurality of streams 91, 92, to the common de-

livery apron 34, of usual construction, and the joint delivery of the plurality of streams of tobacco, as indicated by the arrow is fed to the feeding chute 35 of approved construction, and in turn on the strip of cigarette paper 65 disposed above and controlled by the tube belt 37 of the usual construction and driven by any approved driving mechanism, as will be understood.

In the form of the invention shown in Fig. 1, the bottom of the hopper is formed of the oppositely arranged pin rolls 100, 101, driven by suitable driving mechanism in counter directions shown by the indicated arrows. The pan 102 serves to catch any dust or other undesirable portion of the charge.

In the modification shown in Fig. 2, corresponding parts are designated by like reference numbers, the modification shown in Fig. 2 differing from the construction of Fig. 1 primarily in that the bottom of the hopper is formed of substantially arcuate plates 27, 28, arranged in suitable coaction with the carding rolls 6, 17, similar to the rotating pin wheels 100, 101. In the modification shown in Fig. 2, the tobacco is fed in a form of a plurality of streams, 91, 92, to the common apron 90, and delivered to the similar feeding chute 93 of approved construction in turn feeding the tobacco to the paper strip 94, controlled by the tube belt 95, of usual construction. The regulating means comprises the threaded rods 70, 71, suitably journaled in the end frames 72, 73, the threaded rod 70 carrying the shipper arm 74 controlling the position of the crossed belt 46 relative to the lower cone pulley 42 and the upper cone pulley 44. Similarly, the threaded rod 71 is provided 105 with the shipper arm 75 for controlling the crossed belt 48 relative to its lower cone pulley 43 and its upper cone pulley 45. The threaded rod 70 is provided at one end with the worm wheel 76 meshing with the transverse worm wheel 77 mounted on the regulating shaft 78 provided with the connecting and disconnecting clutch 79, said rod 78 being controlled by the regulating crank arm 80. Similarly, the threaded rod 71 is 110 provided with the worm wheel 81 meshing with the transverse worm wheel 82 carried by the shaft 83 to which the crank arm 80 is also fixed. The regulating shaft 83 is provided with the connecting and disconnecting clutch 84. For simplicity of arrangement, the shaft 83 is shown hollow and receiving interiorly the shaft 78, the shaft 78 passing loosely through a central opening in the worm wheel 82.

Normally, the clutches 79, 84 are in connecting positions, whereby upon turning the regulating crank 80, the threaded rods 70, 71 are rotated in like directions, and shift to like extents and in the same directions 130

the shipper arms 74, 75, and therewith the crossed belts 46, 47, relative to the respective sets of cone pulleys 42, 44, and 43, 45, thus simultaneously adjusting the speeds of 5 the respective shafts 48, 49 and thereby controlling the relative speeds of the respective sets of carding wheels for the two tobacco feeding devices. Upon desiring to adjust the belt 46 without disturbing the adjustment of the belt 47, the clutch 79 controlling the shipper arm 74 of the belt 46 is moved to open position, against the stop 85 indicated in Fig. 5, while the clutch 84 is left in its normal closed position and upon turning 10 the crank arm 80 the threaded rod 71 and its shipper arm 75 are moved to the desired adjusted position. Similarly the belt 46 may be adjusted without disturbing the adjustment of the belt 47 by moving the 15 clutch 84 to its disconnecting position against the stop 86, as indicated in Fig. 5 and turning the crank lever 80 as desired.

With respect to the several forms of my 20 hopper generally, it will be noted that the charge of tobacco positioned between the continuously operated and intermittently operated rolls of the respective sets is subjected to forces of agitation of varying amount and of varying period at any given 25 location within the hopper and further modified in variation of direction of such forces for the different locations within the hopper. Thus, as the charge of tobacco progresses through the hopper, it is effectively agitated to break up lumps or felted 30 masses, to preclude the condition of air pockets and otherwise treat the charge of tobacco to mechanical operations to provide uniform delivery by the respective sets of 35 carding rolls of streams of tobacco of substantially uniform amount and density.

Such improved feeding to the respective 40 sets of carding rolls is even maintained under the condition of partial charge within 45 in the hopper, by reason of the maintenance of contact of such partial charge of tobacco with the respective lower carding wheels 6, 17.

Upon adjustment of the relative speeds 50 of actuation of the respective sets of carding mechanisms, to attain uniform streams of tobacco, and thereby attain a determined uniform total feed of tobacco by the hopper to the rod forming mechanism, incidental 55 variations of any one stream of tobacco from its determined uniform feed is averaged in amount, whereby the total feed of the hopper is maintained substantially constant. It will be noted that when any 60 adjustment of any particular set of carding mechanism is desired, such adjustment may be carried out while the machine as a whole is kept in operation.

Whereas I have described my invention 65 by reference to specific forms thereof, it

will be understood that many changes and modifications may be made, without departing from the spirit of the invention, as defined by the appended claims.

I claim—

1. In a cigarette making machine, a hopper; a plurality of sets of carding devices disposed within said hopper, each set including a carding roll and a pin roll; said sets of carding devices being spaced from 70 one another, and the space within said hopper intermediate said sets of carding devices being substantially free from obstruction for the reception of tobacco, whereby the entire charge of the tobacco within the 75 hopper is substantially wholly supported by said carding rolls and independently of said pin rolls; means for rotatably mounting said carding rolls and means for rotatably mounting said pin rolls in regions respectively without the aforesaid space.

2. In a cigarette making machine, a hopper; a plurality of sets of carding devices disposed respectively toward opposite sides 80 interiorly of said hopper; each set including a carding roll and a pin roll, and the space intermediate said sets of carding devices being free from obstruction for the reception of tobacco, whereby the entire charge 85 of the tobacco within the hopper is substantially wholly supported by said carding rolls and independently of said pin rolls; means for rotatably mounting said carding rolls within said hopper; and means for rotatably mounting each pin roll on a side of its carding roll in a direction toward a side of said hopper whereby to locate said pin roll in an unobstructed region of said 90 hopper.

3. In a cigarette making machine, a hopper; a plurality of sets of carding devices disposed respectively toward opposite sides 95 interiorly of said hopper, each set including a carding roll and a pin roll; the space intermediate said sets of carding devices being free from obstruction for the reception of tobacco, whereby the entire charge 100 of the tobacco within the hopper is substantially wholly supported by said carding rolls and independently of said pin rolls; means for rotatably mounting said carding rolls within said hopper; means for rotatably mounting the pin roll of each set between the carding roll and the adjacent side 105 of said hopper, whereby to locate said pin roll in an unobstructed region of said hopper; and means disposed below said sets of carding devices for conveying the carded tobacco exteriorly of said hopper.

4. In a cigarette making machine, a hopper; two sets of carding devices disposed 110 respectively toward opposite sides interiorly of said hopper, each set including a carding roll and a pin roll; the space intermediate 115 said sets of carding devices being

- free from obstruction for the reception of tobacco, whereby the entire charge of the tobacco within the hopper is substantially wholly supported by said carding rolls and 5 independently of said pin rolls; means for rotatably mounting said carding rolls within said hopper; means for rotatably mounting the pin roll of each set between the carding roll and the adjacent side of said hopper, whereby to locate said pin roll in an unobstructed region of said hopper; speed regulating means for one of said sets of carding devices and separate speed regulating means for the other of said sets of 10 carding devices.
5. In a cigarette making machine, a hopper; a plurality of sets of carding devices disposed within said hopper, each set including a carding roll and a pin roll; said sets of carding devices being spaced from one another and the space within said hopper intermediate said sets of carding devices being substantially free from obstruction for the reception of tobacco, whereby 15 the entire charge of the tobacco within the hopper is substantially wholly supported by said carding rolls and independently of said pin rolls; means for rotatably mounting said pin rolls in regions respectively without the aforesaid space; a driving shaft and gearing including a variable gearing member connecting said shaft with said sets of carding devices.
6. In a cigarette making machine, a hopper; a plurality of sets of carding devices disposed within said hopper, each set including a carding roll and a pin roll; said sets of carding devices being spaced from one another and the space within said hopper intermediate said sets of carding devices being substantially free from obstruction for the reception of tobacco, whereby the entire charge of the tobacco within the hopper is substantially wholly supported by 20 said carding rolls and independently of said pin rolls; means for rotatably mounting said pin rolls in regions respectively without the aforesaid space; a driving shaft and gearing including variable gearing members respectively connecting said shaft with said sets of carding devices.
7. In a cigarette making machine, a hopper; a plurality of sets of carding devices disposed within said hopper, each set including a carding roll and a pin roll; said sets of carding devices being spaced from one another and the space within said hopper intermediate said sets of carding devices being substantially free from obstruction for the reception of tobacco; means for rotatably mounting said carding rolls, means for rotatably mounting said pin rolls in regions respectively without the aforesaid space; a driving shaft; gearing including a variable 25 gearing member connecting said driving

shaft with one of said sets of carding devices and separate gearing connecting said driving shaft with the other of said carding devices and including a separate variable gearing member.

8. In a cigarette making machine, a hopper; a set of carding rolls disposed toward one side of said hopper, said carding rolls being arranged respectively below one another in a direction extending toward the center of the interior of said hopper; a second set of carding rolls disposed toward the opposite side of said hopper, the carding rolls of said second set being arranged respectively below one another in a direction 70 extending toward the center of the interior of said hopper; the upper portion of the central interior of said hopper being free from obstruction for the reception of tobacco; a pin roll coating with said first-named set of carding rolls and disposed on a side of a carding roll of said first-named set adjacent said first-named side of said hopper and a pin roll coating with said second-named set of carding rolls and disposed on a side of a carding roll of said second-named set and adjacent said second-named side of said hopper.

9. In a cigarette making machine, a hopper; a set of carding rolls disposed adjacent one side of said hopper, said carding rolls being arranged respectively below one another in a direction extending toward the center of the interior of said hopper; a second set of carding rolls disposed adjacent the opposite side of said hopper, the carding rolls of said second set being arranged respectively below one another in a direction extending toward the center of the interior of said hopper; the upper portion of the central interior of said hopper being free from obstruction for the reception of tobacco; a pin roll coating with said first-named set of carding rolls and disposed on a side of a carding roll of said first-named set adjacent said first-named side of the hopper; a second pin roll coating with said second-named set of carding rolls and disposed on a side of a carding roll of said second-named set adjacent said second-named side of the hopper and means variable at will for driving said first-named set of carding rolls and said second-named set of carding rolls at the same or different relative speeds.

10. In a cigarette making machine, a hopper; a set of carding rolls disposed toward one side of said hopper said carding rolls being arranged respectively below one another in a direction extending toward the center of the interior of said hopper; a second set of carding rolls being disposed toward the opposite side of said hopper, the carding rolls of said second set being arranged toward the center of the interior of 125

said hopper; the upper portion of the central interior of said hopper being free from obstruction and for the reception of tobacco; a pin roll coating with said first-named set of carding rolls and disposed on a side of a carding device of said first-named set adjacent said first-named side of the hopper; a second pin roll coating with said second-named set of carding rolls and disposed on 5 a side of a carding roll of said second-named set adjacent said second-named side

of said hopper; means for regulating the carded tobacco delivered from said first-named set of carding rolls and delivering the same exterior of said hopper and separate means for regulating the carded tobacco from said second-named set of carding rolls. 15

In testimony whereof I have signed this specification this 9th day of October, 1919.

WILLIAM F. GRUPE.
